Bertrand J. Hoffacker

UNITED STATES PATENT OFFICE.

BERTRAND J. HOFFACKER, OF NEW YORK, N. Y.

SOLDERING-IRON.

SPECIFICATION forming part of Letters Patent No. 319,904, dated June 9, 1885.

Application filed January 22, 1885. (No model.)

To all whom it may concern:

Be it known that I, BERTRAND J. HOFFACKER, a citizen of the United States, residing at New York, in the county of New York and State of New York, have invented new and useful Improvements in Soldering-Irons, of which the following is a specification.

Figure 1 illustrates one form of the device, A being a copper covering of a thickness varying with the weight of the bar used, and adjustable by means of a central cone, *a*, which enters a bore, *a'*, extending from the apex of the bar *B* to a transverse perforation, *c*, with which it communicates. When the bar is to be reheated, its covering may be readily detached by means of a jerking-rod bearing on cone *a*, and somewhat projecting into the transverse perforation *c*, when it is to be placed, apex downward, within a trough-shaped bottomless cast or sheet iron pocket or receptacle, Fig. 3, placed across the furnace-top, and by means of flanges *f f* resting upon its rim. Thus radiation is made of service for heating the covering previous to its use in soldering, while its position obviously is the most practicable for its conjunction with the bar.

Device *A'*, Fig. 2, illustrates a different mode of adjusting the covering to the bar. Angular projection *a* is to extend to the rear of the transverse groove *g*, whereby the insertion of a spike is permitted and a firm conjunction is effected.

Shank *s*, Fig. 1, connects bar *B* and handle *H* by means of screws at its extremities, a nut or tail-plate, *t*, serving to fasten it to the handle, the latter being perforated longitudinally, and having a central tube, *H'*. A shield-plate, *e*, is fastened to the handle by means of clamps *c c* within grooves *g g*, in order to prevent contact of the hand with the shank during use of the tool. Fig. 4 illustrates the shield-plate, which, for a less ponderous tool, serves to connect the handle and shank by means of a nut, *n*, at its reverse side, the perforation of the handle being dispensed with.

Device *S* is a supply-spring, having in its

anterior extremity a triangular perforation for the insertion of a correspondingly-shaped bar of solder, *b*, of optional length, and to be manipulated by thumb-pressure. Thus is effected perfect control of the solder-supply, precluding any waste. By means of a spring-clasp, *c'*, to which *S* is riveted, it may be revolved, and also detached forthwith whenever the bar requires reheating.

Fig. 5 illustrates a cylindriform bar, socket, and shank. It consists of two uniform longitudinal divisions, *D D*, combined by joints *i i* and their socket *H'*. By removing transverse screw *s* either division may be detached, when the screw is to be replaced. The usefulness of the device amply demonstrates itself for working angles of but little compass.

Fig. 6 illustrates a division of this bar device, *A* being its covering. Efficacious connection is had by semicircular projection *o*, bearing wedge-like on conical groove *g*.

What I claim as my invention, and desire to secure by Letters Patent, is—

1. The construction of conical, semi-conical, and rectangular projections attached to square or triangular apex coverings for soldering-irons, in combination with a bar having a bore or groove corresponding to such projections, and a transverse slot or groove through which a spike may be inserted to secure the covering to the bar, substantially as shown, and for the purpose set forth.

2. The construction of a dividable heating-bar and its socket provided with such perforations and grooves as to allow the use of either square or triangular coverings, as specified.

3. The construction of a solder-supply spring, including its anterior triangular perforation and circular fastening-clasp, as described.

BERTRAND J. HOFFACKER.
